Inventor:

J. B. Wilson

My atty:

J. MacCutcheon

United States Patent Office.

JOHN B. WILSON, OF NEW YORK, N. Y.

Letters Patent No. 63,128, dated March 19, 1867.

IMPROVEMENT IN VENEER CUTTERS.

The Schedule referred to in these Letters Patent and making part of the same.

TO ALL WHOM IT MAY CONCERN:

Be it known that I, JOHN B. WILSON, of New York, of the county of New York, in the State of New York, have invented a new Method of Cutting Veneers; and I do hereby declare that the following is a full and exact description thereof, reference being had to the accompanying drawings, making part of this application.

My invention relates to a novel method of cutting veneers, and has for its object to produce, from a plain log, veneers with considerable variety of grain, and from logs possessing "figure," a greater variety of figure than has been obtained by the method of cutting heretofore practised. Previous to my invention it has been customary to slab off the veneers or thin boards from a log with a plain or straight knife in such manner that each cut would take off a stratum of wood equal in length and width to the (cut) surface of the log, and in shape almost a perfect plane, having only the curvature of the arc in which the log was vibrated in the machine. I have discovered that by making the knife or cutting tool of a corrugated or crimped shape throughout its length, and cutting with such shaped knife a veneer which shall be correspondingly corrugated, (crosswise of the veneer,) the veneer will possess a much greater variety of grain or "figure" when pressed out flat or smooth, and find that by so cutting the wood I can produce from a perfectly plain log a figured veneer, and from a log possessing "figure" a more highly or beautifully figured veneer. And my invention consists in producing veneers by cutting them from the log in a corrugated or crimped shape, substantially as hereinafter more fully described.

To enable those skilled in the art to fully comprehend my invention, I will proceed to describe it more in detail, referring to letters in the accompanying drawing, in which I have illustrated a veneer-cutting machine adapted to carry out my invention. In the accompanying drawings—

Figure 1 is a top view of a veneer-cutting machine, having its cutting device so constructed as to produce veneers upon my new method of cutting them.

Figure 2 is a vertical section at line $x x$, fig. 1; and

Figure 3 is an edge view of a veneer as it appears when it comes from the machine.

The general construction and operation of the machine shown, with the exception of the cutting device, is about the same as that of machines already in use, and with which those skilled in the art are familiar. I need therefore only allude to it in a general way.

A is the frame of the machine arranged and supported upon a suitable floor or foundation, B. On the frame A is mounted in suitable bearings or boxes C, a rock-shaft, D, to which is attached the vibratory frame E, to the face of which the log F is secured by bolts in the usual manner. Opposite to the face or log surface of the vibratory frame E is arranged on the frame of the machine the knife-stock or stand G, in which is located the cutting or shaving device. The frame E is vibrated or rocked on its shaft D in the usual manner by means of pitmans, H H, connected to the cranks of any suitable driving machinery, and the boxes, C, are constructed and arranged so as to slide on ways, I I, formed on the frame A, in order that the log F may be fed toward the cutting or shaving mechanism. The feed is effected by means of feed-screws, K K, working through the stands of boxes C C, and arranged in stands m, as clearly seen. The screw-shafts are provided on their outer ends with wheels, N, connected by a belt, O, and may be operated by hand or automatically from the driving mechanism, if deemed expedient. S is the corrugated or crimped cutting or shaving tool or knife, which is arranged in and fastened to the tool-stock G, (as clearly shown,) in such manner as to shave or cut off a thin stratum of the log F, or a "veneer" each time the frame E is fed toward the cutter and caused to descend, as illustrated at fig. 2, where t represents the veneer (in section) being cut by the knife S. As the veneers are cut or slabbed off, they discharge or pass out of the machine, as illustrated (in the direction of the arrow, fig. 2.) The shape of the veneer cut is clearly illustrated in the edge view of the same at fig. 3, from which it will be seen to be of a wave-like or crimped shape. After the veneer is cut of this shape it may be smoothed or pressed flat, and when ready for use will present a plane shape similar to the ordinarily cut veneer. It will be seen by thus cutting or shaving off the wood in corrugated or crimped strata, in lieu of straight with the grain, the different grains of the wood will be penetrated in each cut and shown in the surface of the veneer, and thus the great desideratum of producing a figured veneer from a plain log, or increasing the figure of a log possessing "figure" hereinbefore alluded to, is accomplished. Of course the form and size of the corrugations in the knife may be infinitely varied without departing from the spirit of my invention, and it may be even possible to cut the veneer

in the manner or shape described without a corrugated knife, by shaving it off longitudinally. I therefore wish it to be understood that I do not propose to limit my claim of invention to the peculiar form of knife shown, or to any details of machinery, but having explained the objects and advantages of my invention, and the mode in which I have successfully carried it out or practised it,

What I claim as new, and desire to secure by Letters Patent, is—

Cutting a crimped or corrugated veneer, substantially as described, for the purpose set forth.

In testimony whereof I have hereunto set my hand and seal this 24th day of January, 1867.

JOHN B. WILSON. [L. S.]

In presence of:

J. N. McINTIRE,

CHARLES SPEER.
